C. B. ROBUCK,
RAILWAY CROSSING,
APPLICATION FILED JULY 2, 1917.

1,317,394.

Patented Sept. 30, 1919.

UNITED STATES PATENT OFFICE.

CHARLES B. ROBUCK, OF LOS ANGELES, CALIFORNIA.

RAILWAY-CROSSING.

Specification of Letters Patent. Patented Sept. 30, 1919.

1,317,394.

Application filed July 2, 1917. Serial No. 178,150.

To all whom it may concern:

Be it known that I, CHARLES B. ROBUCK, a citizen of the United States, residing at Los Angeles, in the county of Los Angeles and State of California, have invented certain new and useful Improvements in Railway-Crossings, of which the following is a specification.

My invention relates to improvements in railway crossings and frogs and especially crossings which ordinarily have gaps or recesses for the passage of the wheel flanges of the rolling stock of the road, and where the corners of the crossings are apt to become defective and broken under the pounding of the wheels.

It is an object of my invention to provide a crossing in which the flanges of the wheels raise the tread portions from the said crossing and eliminate all noise due to wheels jumping across the flange grooves.

It is a further object of my invention to provide replaceable wearing blocks or members at the intersecting corners of the said cross grooves of the crossing, so that new corners may be set into the body of the crossing and secured by any simple means which is located at convenient positions on the crossing and accessible without the removing of the entire crossing structure from the road bed.

It is a still further object of my invention to provide a crossing with a removable groove section and to have the approaching end portions inclined, so that the flange of a wheel will roll up on the groove section gradually and raise the tread off the wheel off the crossing frame, thereby preventing the wheel from striking the corners of the grooves while the wheel passes thereby.

It is a still further object of my invention to cushion the replaceable groove and corner blocks or members with a soft but durable material, whereby the double wear upon the groove members and the corner blocks due to the wheels passing in different directions will be greatly reduced.

With these and other objects in view, my invention comprises certain novel constructions, combinations and arrangements of parts as will be hereinafter more fully described and claimed.

In the accompanying drawing forming a part of this specification:

55 Figure 1 is a plan view of an assembled

crossing showing the detachable groove members and corner blocks in place.

Fig. 2 is a cross sectional view of the crossing taken on the line 2—2 of Fig. 1.

Fig. 3 is a cross sectional view of one of the frogs of the crossing taken on the line 3—3 of Fig. 1.

Fig. 4 is a cross sectional view of a portion of a crossing taken on the line 4—4 of Fig. 1.

Fig. 5 is a plan view of a portion of a crossing showing a modified form of a detachable corner block.

Fig. 6 is a cross sectional view of a modified form of the crossing taken on the line 6—6 of Fig. 5.

In the accompanying drawing two forms of the invention have been illustrated and the details and features of the invention will now be more specifically described and claimed, reference being had thereto. In the drawing, 8 indicates the body portion or frame of a railroad crossing, the angle of intersection being represented as 90°. The frame is provided with grooves 9 which have replaceable groove members 10 lying therein. These groove members are formed with the approaching ends as 11 and 12 being inclined, the inclination stopping at the edge of the recess 17, the intermediate distance as 14 being horizontal or parallel at the top of the frame of the crossing. The ends of these groove members are secured to the frame of the crossing by bolts 15 which may be welded or secured in any other convenient manner; these bolts extend through the body portion 8 of the crossing and are tightened thereto by a nut 16. It will be observed that these groove members may be replaced at any time by loosening the bolt 15, whereby the said members may be detached from the frame of the crossing.

At the intersecting groove points are recesses 17 formed in the frame of the crossing, so that a detachable corner block 18 may be set therein above the groove member 10, as is clearly shown in Fig. 2 of the drawing. These groove members are formed so as to make a continuous flange engaging member, and are held in the recess 17 by bolts 19 or in any other suitable manner, which may be later determined.

It will be observed that these corner blocks 18 do not extend in depth to the bottom of the groove member 10, but are of

ample depth to insure the proper strength required at the intersections of the grooves where the double wear upon the crossing occurs due to the wheels rolling in both 5 directions.

It will also be observed that the inclination 11 of the groove members is so gradual that there is no danger of a wheel jumping when the flange begins to roll up upon the 10 groove members. The bolts 19 are so placed with respect to the grooves that they can not be touched by the tread of a wheel as there is ample distance between them and the edge of the adjacent groove.

15 It will also be observed that the bolts 15 which are shown welded to the groove members in this particular instance are beneath the grooves and entirely away from the flange of the wheel.

20 In the modified form shown in Fig. 5 which represents a portion of a crossing or a frog, the detachable groove member 20 has a block 21 seated therein in the form of a cross; this block is detachable and held in 25 place by any suitable means as a bolt 22. By making the form of this block the shape of a cross, it will be observed that as the flange of the wheel travels in both directions across this intersecting point, the wear on said 30 block is twice as much as at any intermediate point and may be readily replaced. Between the under surface 23 of the groove member 20 and the frame 24 is a cushion member 25 made up of a soft durable material such as silk, or other fabric whereby 35 the groove member 20 and the corner block 21 setting in said groove may be cushioned, so as to overcome as much wear as possible upon the groove member. Formed in the 40 frame of the crossing 24 is a hole or opening 26, which allows the head of the bolt 22 to set therein, whereby the corner may be replaced by loosening the nuts 27 of the said bolt 22. By this construction, it will be ob- 45 served that the corner block, groove member and cushioning material is rigidly held to-

gether and may be replaced at any time. The replaceable parts of the crossing have been so designed as to be changed at any time without completely removing the whole 50 crossing structure from the road bed, there being ample room for any workman to loosen the securing means of the said parts from the upper surface of the crossing structure.

The groove members and corner blocks 55 have their edges curved upwardly as at 29. These upwardly turned edges form fillets in the grooves and insure a more perfect alignment of the wheels while passing over the crossing and at the same time preventing 60 the flanges from striking or rubbing the upper edge 30 of the said grooves thereby overcoming any wear on the wheel flanges which soon become sharp and untrue.

It is understood that the details of the 65 device may be varied, and mechanical equivalents substituted therefor without departing from the spirit of the invention. The openings 28 in the center of the crossing may be covered by a plate if it is found 70 necessary at certain locations where the said crossing is to be installed.

Having thus described my invention what I claim is:

1. A noiseless railway crossing having 75 grooves formed therein, flange engaging members lying in said grooves, replaceable wearing corners adapted to be set in said members, the approaching end portions of said flange engaging members being inclined upward toward said wearing corners.

2. A noiseless railway crossing having flange grooves formed therein, detachable flange engaging members seated in said grooves, corner blocks set into said members, means for securing said flange engaging members in said grooves, and means for detachably securing the said corner blocks in said flange engaging members.

In testimony whereof, I have hereunto set 90 my hand.

CHARLES B. ROBUCK.
